(57) **CLAIM**

We claim the ornamental design for a vehicle hood, as shown and described.

DESCRIPTION

FIG. 1 is a front perspective view of the claimed design; FIG. 2 is a front view of the claimed design; FIG. 3 is a rear view of the claimed design; FIG. 4 is a left side view of the claimed design; FIG. 5 is a right side view of the claimed design; FIG. 6 is a top view of the claimed design; FIG. 7 is a bottom view of the claimed design; and, FIG. 8 is a detailed front perspective view of the claimed design.

The ornamental design that is claimed is shown in solid lines in the figures. Evenly-spaced broken lines depict unclaimed environmental subject matter.

1 Claim, 8 Drawing Sheets
